UNITED STATES PATENT OFFICE.

JASPER F. CULLIN, OF DETROIT, MICHIGAN, ASSIGNOR, BY MESNE ASSIGNMENTS,
TO WILLIAM J. HARTWIG, OF DETROIT, MICHIGAN.

INSULATION FOR ARMATURES.

1,392,557.

Specification of Letters Patent.

Patented Oct. 4, 1921.

Application filed December 29, 1919. Serial No. 348,087.

To all whom it may concern:

Be it known that I, JASPER F. CULLIN, a citizen of the United States, and residing at Detroit, in the county of Wayne and State 5 of Michigan, have invented a new and Improved Insulation for Armatures, of which the following is a specification.

This invention relates to the insulation of the windings of the armatures of electric 10 machines, and consists in simple and effective means to prevent electric currents from passing from one winding to another or from the windings to the core of the armature.

15 This invention consists in the details of construction illustrated in the accompanying drawings and particularly pointed out in the claims.

In the drawings, Figure 1 is a plan of a 20 motor armature partly wound. Fig. 2 is a view of the front or commutator end thereof. Figs. 3, 4 and 5 are sections on the lines 3—3, 4—4, and 5—5 of Fig. 1. Fig. 6 is a view of the rear end of the armature. Figs. 25 7 and 8 are developments illustrating the construction of the armature. Fig. 9 is a perspective of a flat copper rod constituting a winding of this armature. Fig. 10 is a view of a piece of insulation.

30 Similar reference characters refer to like parts throughout the several views.

The shaft 1, the laminations 2 of the core of the armature and the segments 3 and spool 4 of the commutator as well as the 35 spacing collar 5 between the core and the commutator are of well known construction. Bars or rods which constitute the windings of the armature are usually increased in woven cotton sleeveings which are properly 40 treated to render them good insulations, but in the present construction no such fabrics are employed.

The laminations are formed with an unequal number of notches 6 in the usual manner, the present drawings showing 21 and also the same number of segments of the commutator, each segment having a radial projection 7 provided with a notch 8 to receive the ends of the bars A which constitute the windings. These bars are of copper and comprise the eyes 9, and two sections, each consisting of an inclined portion 10, a longitudinal part 11, an inclined portion 12 and an end 13. The insulation of

these windings can best be pointed out by 55 describing the manner of positioning these bars A.

Tough and strong strips 15 of paper-like insulation, bent U-shaped, are first placed in the grooves in the armature core, after 60 which the straight portion 11 of one section of each winding is driven down to the bottom of its groove. During this process, the other section of each winding is swung out to permit a narrow tool to be inserted in the 65 grooves in the core to drive the first sections to the bottom of the grooves. At the same time, the ends 13 of these first sections are also driven down to the bottoms of the notches 8 in the commutator segments. 70

During the positioning of these first sections, a ribbon 16 of indurated fiber, rubberized duck or other good insulating material is woven in over and under the inclined portions 10 of the first sections, as indicated in 75 Figs. 5, 6 and 7, so as to insulate these portions 10 of adjacent windings from each other. After this a similar ribbon 18 is wound around all the portions 12 at the commutator end of the armature. 80

A narrow strip 19 of good insulating material is now laid in each groove in the core and the second section of each bar A is bent down and driven into its proper groove onto this insulation. These grooves in the core 85 must be made of such width that the parts 11 of the bars A must be driven in with considerable force but without destroying the insulating strips 15 which line these grooves. The ends 13 of the second sections of these 90 bars are driven into proper notches in the commutator segments where they are soldered in place later on. The described insulation has been found sufficient and satisfactory for the starting motors for automobile 95 engines, which motors are operated by comparatively low current. The most desirable insulation 19 between the parts 11 of the bars A is produced by twisting a narrow strip of insulating paper into a cord or tube, 100 as indicated in Fig. 10, which seems to accommodate itself to the slight undulations which sometimes occur at the edges of the parts 11 of the windings, and seldom if ever do short circuits occur through these 105 twisted strips.

The details and proportions of these insulations may all be changed by skilled

electricians without departing from the spirit of my invention as set forth in the following claims.

I claim:

- 5 1. A cylindrical armature core provided with evenly spaced longitudinal grooves, armature windings comprising metal bars bent on themselves substantially midway their length to constitute two sections, a pair
- 10 of sections of two windings being positioned in each groove, one inside of the other, means to insulate the windings in each groove from each other and from the core, and a strip of insulating material woven
- 15 in and out between the inner sections of the windings adjacent one end of the armature and extending generally circumferentially of the armature.

2. A cylindrical armature core provided with evenly spaced longitudinal grooves, 20 armature windings comprising metal bars bent on themselves substantially midway their length to constitute two sections, a pair of sections of two windings being positioned in each groove, one inside of the other, means to insulate the windings in each groove from each other and from the core, and a strip of insulating material woven in and out between the inner sections of the windings adjacent one end of the 25 armature and extending generally circumferentially of the armature and flat strips of insulation extending around the inner sections and within the outer sections of the windings at both ends of the armature.

JASPER F. CULLIN.
